(57) **CLAIM**

I claim the ornamental design for a fishing lure, as shown and described.

DESCRIPTION

FIG. 1 is a right front perspective view of a fishing lure showing my new design;

FIG. 2 is a right side elevational view thereof, the left side elevational view being a mirror image of the right side elevational view;

FIG. 3 is a top plan view thereof;

FIG. 4 is a bottom plan view thereof;

FIG. 5 is a front elevational view thereof; and,

FIG. 6 is a rear elevational view thereof.
